METHOD OF AND DEVICE FOR COOLING THE
COMPONENT ELEMENTS OF MACHINESOtto Arthur David, Dammarie les Lys, France, assignor
to Societe Nationale d'Etude et de Construction de
Moteurs d'Aviation, Paris, France, a French Company

Filed May 14, 1958, Ser. No. 735,243

Claims priority, application France May 28, 1957
2 Claims. (Cl. 253—39.15)

When the component elements of a machine, and more particularly of a heat engine, have to work at elevated temperatures, technological problems are encountered which are quite difficult to solve since the maximum temperature permitted by present known materials is relatively low.

Recourse has therefore been had to cooling these elements by subjecting them to the action of a fluid having a low temperature.

If the action of the cooling fluid is effected by simple circulation thereof along one face of the element to be cooled, that is to say if the cooling fluid only washes along the said face as in the case of conventional cooling by circulation, there is a risk that the distribution of temperature at the cooled element may not be uniform. This is particularly the case if the various parts of the element to be cooled are subjected to different temperatures and if on the other hand the fluid travels along a duct or conduit wherein the temperatures vary and along which the cooling fluid itself becomes heated.

This non-uniform distribution causes stresses in the molecular structure of this element, and diminishes the mechanical strength thereof.

The present invention is concerned with a more rational cooling method which obviates the defects mentioned hereinbefore. According to this method, the cooling fluid is made to arrive at a uniform temperature through a jacket which itself has a substantially uniform temperature distribution, and at a pressure greater than the pressure prevailing externally of the jacket, the said fluid escaping from the jacket through appropriately formed and distributed perforations in the form of fine jets perpendicular to the wall which is to be cooled, so that the cooling fluid impinges violently against the said wall, instead of merely washing along it as in the case of the conventional methods.

Tests carried out by the applicant have shown conclusively that the action of jets of cooling fluid directed perpendicularly to the hottest parts is distinctly superior to what can be obtained by simply washing along a part with the said fluid, and that the heat transfer obtained, for example at a blade profile, is markedly increased.

The present invention also extends to cooling devices carrying the said methods into effect, and to component elements of machines arranged so as to permit the said method to be carried into effect.

The description which will now be given with reference to the accompanying drawings will show clearly the various features of the invention and the manner of carrying them into effect, any feature brought out from the text and from the figures being of course understood to come within the scope of the present invention.

FIG. 1 is a diagrammatic sectional view taken on the line I—I of FIG. 2, of a guide blade of the turbine of a turbo-jet engine.

FIG. 2 is an elevational view of this blade with a portion thereof broken away.

FIG. 3 is a detail view showing the form of an inner jacket which is lodged in such a blade.

The form of embodiment illustrated by way of example in FIGS. 1 and 2 is concerned with a hollow blade 1 made of sheet metal which is to be subjected to cooling

2

by internal circulation of air and is welded along the trailing edge on a rib 2 in which are formed apertures 3 whereby the air which has been used for cooling can escape from the blade and mingle with the passing flow of hot gases.

According to the present invention, a jacket 4 is fitted in the interior of this blade. It is so dimensioned and profiled that between the wall of the blade and the said jacket there is formed a space 9 which is sufficient to permit the circulation of the cooling air. This jacket, closed at its upper end by a wall 5, is held in place by bosses 6 (FIG. 3) which bear against the wall 1 of the blade and are staggered in a quincunx formation.

The jacket 4 comprises holes or perforations 8 situated opposite those parts of the blade wall which are to be more particularly cooled, that is to say the parts where there is a risk of excessive heating. In the example illustrated in the drawings, the perforations 8 have been provided in the vicinity of the leading edge of the blade and also in the vicinity of the trailing edge thereof.

The cooling air can be taken from the output side of the compressor and penetrates into the jacket 4 through the root of the blade in the direction of the arrows 7. It issues from the jacket through the perforations 8 in the form of fine jets which strike perpendicularly against the wall of the blade exactly at the points to be cooled.

This air circulates then through the space 9 in the direction of the arrows 10 and finally escapes therefrom through the apertures 3. It should be noted that the staggered bosses 6 increase the turbulence of the air circulating in the space 9 and promote heat exchange.

The thin jets issuing from the perforations 8 and impinging perpendicularly against the wall of the blade 1 produce a cooling effect by impact which gives better results than simple circulation of air through a blade. The method of cooling according to the invention therefore makes it possible, by sending through appropriately arranged perforations jets of air directed perpendicularly to the parts to be cooled, to obtain a better efficiency since on the one hand the air is still relatively cool when issuing from the perforations 8 and its temperature is the same at perforations situated near the blade root and perforations situated near the blade tip, and on the other hand, this air not being heated as it passes through the jacket 4, the heat exchange over the whole height of the blade will be more uniform and therefore stresses caused by great differences in temperature can be avoided.

In the preceding description the example chosen has been an entry guide blade for a gas turbine. However it will be apparent that the invention can be applied to any other component element of a machine which has to be effectively cooled, and more particularly to the rotor blades of the turbine, to support arms situated in the flow of hot gas or to the walls of the combustion chamber or the post-combustion duct.

What I claim is:

1. A gas-turbine hollow blade having a leading edge and a trailing edge, with an orifice formed through the said trailing edge, said blade comprising internal means for discharging a coolant gas under pressure onto the inner surface of the leading edge of said hollow blade, means for directing said coolant gas as a thin flow in bathing contact with the inner surface of said hollow blade from the leading edge to the trailing edge thereof, to be discharged through said orifice, and further internal means for discharging additional fresh coolant gas onto the inner surface of said hollow blade adjacent and in advance of the trailing edge thereof, in a substantially transverse direction with respect to said thin flow.
2. A gas-turbine hollow blade having a leading edge and a trailing edge, with an orifice formed through the said trailing edge, said blade comprising an inner cham-

ber having a wall extending substantially parallel and close to the inner surface of said hollow blade to define therewith a narrow passage extending from the leading edge of said blade to said orifice, a supply of coolant gas under pressure to said chamber, a first series of nozzles formed through said wall opposite the inner surface of said leading edge to discharge thereonto a fraction of the coolant gas supply which is thereby caused to flow towards said orifice through said narrow passage in bathing contact with the inner surface of said hollow blade, 10 and a second series of nozzles formed through said wall opposite the inner surface of said hollow blade adjacent the trailing edge thereof, said latter-mentioned nozzles being directed transversely with respect to said narrow passage.
